His Attorney.

UNITED STATES PATENT OFFICE.

WILBUR O. WILSON, OF CHICAGO, ILLINOIS.

CABLE-SPICE.

1,167,962.

Specification of Letters Patent. Patented Jan. 11, 1916.

Application filed December 12, 1913. Serial No. 806,175.

To all whom it may concern:

Be it known that I, WILBUR O. WILSON, a citizen of the United States, and a resident of the city of Chicago, county of Cook, and State of Illinois, have invented certain new and useful Improvements in Cable-Splices, of which the following is a specification.

My invention relates to improvements in cable splices and has for its object the provision of an improved cable splice which may be readily detached for testing purposes and which has high resistance.

The invention consists in the combinations and arrangements of parts hereinafter described and claimed.

The invention will be best understood by reference to the accompanying drawing forming a part of this specification, and in which—

20 Figure 1 is a longitudinal section of a splice embodying my invention, and Fig. 2, a section taken on line $x-x$ of Fig. 1.

The preferred form of construction as illustrated in the drawing comprises two 25 lead casings or tubes 1 and 2 which are secured to the ends of the ordinary lead pipe or casing 3 surrounding the cable sections, said cable sections being provided with the usual insulation 4 and the wire 5. Each of 30 the casings 1 and 2 is secured to the corresponding lead pipe 3 by means of a wiped soldered joint 6 as shown.

A metallic socket member 7 is secured to the end of one of the wires 5 and a metallic 35 plug 8 is secured to the end of the other wire 5 and is adapted to fit within socket member 7, plug 8 being provided with transverse slits 9 to afford resiliency thereto and thus effect a good electrical connection. A 40 tube 10 of insulating material is arranged in casing 2 surrounding member 7 and the insulation 4 as shown, said tube extending to the end of socket member 7. The portion of plug 8 adjacent the end of the corresponding wire is covered with an insulation 11 which may be of insulating tape if desired, said insulation 11 extending about half the length of plug 8 so as to leave a portion of said plug protruding for entry into socket 45 7. An insulating tube 12 is fitted over insulating tube 10 and projects around insulation 11 so as to further insulate the connection and to break or cover the joint between insulating tubes 10 and 11. Another 50 insulating tube 13 is placed in casing 1 around the usual insulation 4 as shown.

This arrangement effects an insulation of the joint between the wires of very high resistance.

A threaded head 14 is soldered to the end 60 of casing 2, the end 15 of said casing being upset against the end of said head as shown to further strengthen the connection. Another head 16 is soldered to the end of casing 1 with the end 17 of said casing upset over 65 the end of head 16 to strengthen this connection. A threaded sleeve 18 is swiveled to head 16 and threaded on head 14 to effect a swiveled threaded union between said heads to hold said parts together. A gasket 70 19 of rubber or other suitable material is interposed between the upset ends 15 and 17 of casings 2 and 1 respectively so as to insure the forming of a water tight joint. By this arrangement a connection between 75 the ends of wire sections 5 is effected which may be readily detached for testing purposes and which has great resistance to the escape of current and is also perfectly water tight.

While I have illustrated and described the 80 preferred form of construction for carrying my invention into effect, this is capable of variation and modification without departing from the spirit of the invention. I, therefore, do not wish to be limited to the 85 precise details of construction set forth, but desire to avail myself of such variations and modifications as come within the scope of the appended claim.

Having described my invention what I 90 claim as new and desire to secure by Letters Patent is:

A device of the class described comprising two cable sections, lead pipes encircling said cables, a casing section of larger diameter 95 secured to the end of each of said pipes, means for securing the ends of said casings together, a socket member secured to the end of the wire of one cable, a plug secured to the end of the wire of the other cable section, a tube of insulating material surrounding said socket member throughout its length and extending over the entire portion of the respective cable end within the casing member, a similar tube having one 100 end thereof arranged between the last mentioned tube and the casing and projecting beyond said socket member, insulation inclosing said plug except the portion adapted to fit within said socket, the end of said insulation being adapted to abut the end of the socket member and the tube immediately 105 110 115

surrounding the same, insulation arranged between the cable end bearing the plug and its respective casing member and the projecting end of the insulating tube on the socket end adapted to extend over the insulation on the plug and adjacent portion of the cable and abut the last mentioned insulation, substantially as described.

In testimony whereof I have signed my name to this specification in the presence of 10 two subscribing witnesses.

WILBUR O. WILSON.
